Primary Examiner — Barbara Fox*Assistant Examiner* — Kristin E Reed(74) *Attorney, Agent, or Firm* — Simpson & Simpson, PLLC(57) **CLAIM**

The ornamental design for a drapery rod support assembly, as shown and described.

DESCRIPTION

FIG. 1 is a top perspective view of a drapery rod support assembly showing the present invention, shown holding draperies;

FIG. 2 is a top perspective view thereof, shown with the draperies removed;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines showing draperies in FIG. 1 depict environment and form no part of the claimed design.

1 Claim, 5 Drawing Sheets(56)
